A. WALL.

APPARATUS FOR CARBONATING LIQUIDS.

(Application filed Oct. 6, 1899.)

(No Model.)

Fig. 1

UNITED STATES PATENT OFFICE.

ALFRED WALL, OF RAMSEY, ENGLAND.

APPARATUS FOR CARBONATING LIQUIDS.

SPECIFICATION forming part of Letters Patent No. 660,740, dated October 30, 1900.

Application filed October 6, 1899. Serial No. 732,799. (No model.)

To all whom it may concern:

Be it known that I, ALFRED WALL, brewer, a subject of the Queen of Great Britain and Ireland, and a resident of Lezayre road, 5 Ramsey, Isle of Man, England, have invented a certain new and useful Apparatus for Carbonating Liquids, of which the following is a specification.

The object of my invention is to provide an 10 improved apparatus for carbonating liquids.

The process of carbonating liquids by carbonic-acid gas has been done heretofore before bottling, and by means of my invention this process can be accomplished after bot- 15 tling.

Referring to the drawings which form a part of this specification, Figure 1 represents an elevation of the apparatus, shown partly in section. Fig. 2 is an enlarged section of 20 an improved self-acting stopper forming part of this invention, Fig. 3 being an outside view of the same; and Fig. 4 is an enlarged section of the tube and valve for inserting in the stopper when carbonating in the manner hereinafter described.

In the several views, A is the bottle the liquid in which is required to be carbonated; B, the improved self-acting stopper, which is fitted to the neck C of the bottle.

30 D is the tube inserted in the end of the stopper B, having a rubber-cork-connecting cone E and loose brass washer F. The said small tube has a miter valve end G and passes through the screwed valve-seating H and is

35 kept gas-tight by the stuffing-box I, formed by the nut J. This screwed valve-seating H is screwed to the inlet-piece K by means of the nut L. The aforesaid small tube D is hollow for a greater part of its length, as

40 shown at M, and is provided with a small hole N, leading from this hollow portion to the outer surface of the tube. This small hole forms the automatic inlet, to be hereinafter described. The coil-spring O serves to keep

45 the tube D pressed upward, with the miter end resting against the seating H. The gas is admitted through the inlet P from the pressure-reservoir or gas-supply into the chamber of the inlet-piece K, but cannot escape 50 further on account of the small tube D being close against the seating H by the action of the coil-spring O.

The process of carbonating takes place in the following manner: The bottle already filled with the liquid is stoppered by the improved stopper aforesaid. This stopper is made in such a way, as shown by the detail section in Fig. 2, that the gas or any other material to be admitted into the bottle can be so admitted through said stopper, but cannot escape back again. To do this, I form a hole B' through the stopper lengthwise and nearly along its length, and at the inner termination of said hole I form another at right angles, extending from the center to the side, 65 as shown at B². This hole is covered by an india-rubber tube or band B³, which envelops the outer surface of said stopper. The bottle and stopper are placed in an inverted position in a suitable frame or stand R, the upper 70 portion of which has a stem Q, terminating in a flange S at its lower end, the upper end sliding in a socket T, containing a spiral spring U to keep said stem bearing down upon the base of the bottle. The sliding socket 75 has an eye at its upper end and in its turn slides up and down in the frame and is controlled by the lever V. When the bottle is in position, the lever V is raised and puts a pressure on the bottle against the upward 80 pressure of the spring O and so depresses the small tube D, forcing it downward till the side hole N is exposed to the chamber of the inlet-piece K, and the gas rushes through the small tube D and the improved stopper B into 85 the bottle. When the liquid has been sufficiently carbonated, the handle of the lever V is pulled down, thereby releasing the pressure on the bottle, and the india-rubber ring B³ on the stopper B prevents any escape of gas from 90 the bottle, and at the same time the spring O forces the miter end of the small tube D against its seating and shuts off communication from the gas-inlet P through the small hole N, and this lower valve is thus automatically closed and the bottle can be removed. 95

Having now described my invention, what I claim as new, and desire to secure by Letters Patent, is—

In a fluid-carbonating apparatus the combination of a frame, a reciprocating resilient bottle-carrying stem carried by the frame, a conical tubular cork for the bottle having a lateral inlet and provided with a flexible band

surrounding the sides of said cork and lateral inlet, a spring-retracted reciprocating tube exteriorly coned at its outer end and having an elastic cone-washer adjacent thereto 5 adapted to enter said tubular cork, a valve at the inner end of the tube, a valve-seat and housing for the tube and connections with a source of fluid-supply, whereby the bottle is

held and filled by inserting the tube and cone within the bottle-neck.

In witness whereof I have hereunto set my hand in presence of two witnesses.

ALFRED WALL.
